UNITED STATES PATENT OFFICE.

WILLIAM B. MAY, OF DENVER, COLORADO.

MITER-BOX.

SPECIFICATION forming part of Letters Patent No. 727,820, dated May 12, 1903.

Application filed June 3, 1902. Serial No. 110,089. (No model.)

To all whom it may concern:

Be it known that I, WILLIAM B. MAY, a citizen of the United States, residing at Denver, in the county of Arapahoe and State of Colorado, have invented a new and useful Miter-Box, of which the following is a specification.

My invention relates to improvements in miter-boxes in which an adjustable angle-guide operates in conjunction with a rectangular base, a U-shaped steel-spring saw-guide clamp, and a common hand or back saw; and the objects of my invention or improvement are, first, to provide an accurate and expeditious means of cutting material for wood-working at any angle desired and without the aid of bevel or try squares; second, to afford by reason of its simplicity, lightness, and compact form a valuable addition to the carpenter's and cabinetmaker's shoulder-box; third, to provide a means whereby woodworking material of any width and thickness may be operated easily and accurately and under conditions in which a larger miter-box could not be used; fourth, to provide a simpler, cheaper, and much better miter-box than any heretofore made. I attain these objects by the mechanism illustrated in the accompanying drawings, in which—

Figure 1 is an isometric projection of the entire device attached to a common hand-saw. Fig. 2 is a side view of the device with the exception of the adjustable angle-guide. Fig. 3 is a face view of the bottom surface of the base of the device with adjustable angle-guide omitted. Fig. 4 is a side view of the adjustable angle-guide separated from the base. Fig. 5 is a perspective view of the angle-guide, and Fig. 6 is an end view of the latter.

Similar letters refer to similar parts throughout the several views.

The base C, the U-shaped steel spring S, the fixed saw-guide g, the movable saw-guide g', attached to the free end of said spring, the adjustable angle-guide G, the bolt b, and the thumb-nut n constitute the framework of the device. The U-shaped spring S and the saw-guides g g' attach the saw to the device and keep it in true cutting-line when in operation, with the angles formed by the adjustable angle-guide operated by the bolt b, the thumb-nut n, and the dowel-pins p p, which

engage the countersunk holes in the base C, Fig. 3, at a a', d d', i i', and f f', respectively, accordingly as the angle-guide G is attached to the base C by the bolt b in the central hole k in Fig. 3 or in the lateral hole k'. When the angle-guide G is attached by the bolt passing through the hole k in the center of the base C, a right-angled cut is made, or an angle of forty-five degrees may be cut to the right or left. When the angle-guide G is attached by the bolt b passing through the lateral hole k', an accurate square cut can be made.

Any angle whatsoever may be cut by reversing the bolt b in the adjustable angle-guide G and attaching it to the base C in the hole k. In this case the dowel-pins p p will also be reversed, and they will not engage the countersunk holes before mentioned.

The countersunk holes at z z, Fig. 4, (indicated by dotted lines,) are for the purpose of attaching the miter-box securely to a bench by screws, if desired, for stability. In Fig. 1 the saw-guide g is firmly fixed to the base C by screws or other means and strengthened by one or more corner braces or brackets x x, also fastened by screws.

The U-shaped steel spring S is firmly fastened to the fixed saw-guide g by screws, the opposite saw-guide g' being attached in a similar manner to the free end of the U-shaped steel spring S.

The miter-box framework and adjustable angle-guide may be constructed either of wood or metal, as desired.

The inner surfaces of the saw-guides g g' adjacent to the saw-blade, which may be of the ordinary handsaw variety or a back-saw, are smooth, and the strength of the spring S is sufficient to not only attach the device to the saw, but also to keep it in true cutting-line without "binding." The dimensions of a practical working model of my invention are: length, five inches; width, three inches; height, seven inches.

What I claim as my invention, and desire to secure by Letters Patent, is—

1. In a miter-box, the combination with a base having a central perforation and a series of holes surrounding the said perforation, a second perforation in the said base, of an angle-guide having projections upon its

upper surface, said base being interchangeably mounted in said perforations, the projections of the angle-guide being interchangeably registerable with the holes in the base, 5 an upright fixedly mounted upon one end of the base, and an inverted-U-shaped spring secured to the fixed upright and carrying a member upon its free end disposed opposite the said fixed upright whereby a saw-guide 10 is formed between the two latter elements.

2. In a miter-box, the combination with a base having an upright disposed at one end thereof and depressions in its under surface, of an angle-guide having projections upon its 15 upper surface, said base being removably and adjustably mounted upon said angle-guide, the projections of the angle-guide being interchangeably registerable with the said depressions of the base, an inverted-U-shaped 20 spring having one of its ends secured to the said upright and carrying a member at its free end disposed opposite the upright whereby a saw-guide is formed between the two latter elements.

25 3. The combination with a base having

holes in its under surface, an inverted-U-shaped spring mounted upon the base, a saw-guide, and an angle-guide removably, and adjustably connected with the base, said angle-guide carrying projections upon its upper 30 face, said projections engaging the holes in the under surface of the base.

4. In a miter-box, the combination with a base having a central perforation and a series of holes surrounding the perforation, a 35 second perforation in said base, of an angle-guide having projections upon its upper surface, said base being interchangeably mounted in said perforations, and a saw-guide connected with the base, the said projections being 40 interchangeably registerable with the holes in the under surface of the base.

In testimony whereof I have signed my name to this specification in the presence of two subscribing witnesses.

WILLIAM B. MAY.
